UNITED STATES PATENT OFFICE.

CHARLES ABRELL AND EDWARD BURJES, OF ALTON, ILLINOIS.

BRUSH.

SPECIFICATION forming part of Letters Patent No. 590,871, dated September 28, 1897.

Application filed February 1, 1897. Serial No. 621,482. (No model.)

To all whom it may concern:

Be it known that we, CHARLES ABRELL and EDWARD BURJES, citizens of the United States, residing at Alton, in the county of 5 Madison and State of Illinois, have invented certain new and useful Improvements in Hydraulic Tools, of which the following is a specification.

Our invention relates chiefly, but not solely, 10 to improvements in devices for use in bathing, washing, or scrubbing; and the main objects of our improvements are, first, to provide improved means for supplying brushes for washing or scrubbing with water, and, second, to make the water set the brushes to 15 which it is supplied in motion, and cause such brushes to wash or scrub any surface with which they may be brought in contact. We attain these objects by mechanism whose preferred form is illustrated in the accompanying 20 drawings, in which—

Figure 1 is a sectional elevation of the preferred form of the device. Fig. 2 is a view taken at right angles to the one shown in Fig. 25 1 with the brush removed and the handle broken away. Fig. 3 is an end view with the brush removed. Fig. 4 is a detailed sectional elevation of a portion of the device; and Fig. 30 5 is an enlarged detailed view on line 5, Fig. 1, looking inward.

Similar letters refer to similar parts throughout the several views.

A represents a tubular inlet for water. Its inner end a is closed and its outer end a' is open, and it is shown screw-threaded at a^2 . It is provided with a pair of oppositely-directed nozzles a^3 and an annular flange or shoulder a^4 , and from its closed end a rod a^5 projects. Over the outer end of the inlet A 35 the inner end of a tubular handle a^6 is screwed, and to this handle a cock a^7 is attached, to which a hose a^8 is shown secured.

B represents a casing, which in the form shown is composed of an inner part B' and an outer part B². The part B' has an end b , which encircles the inlet A, and a collar b' , which is shown secured to said inlet between said annular flange a^4 and the handle a^6 by means of a set-screw b^2 . From the outer edge 45 50 of the end piece b an annular flange b^3 projects and is shown provided with an L-shaped slot b^4 for the reception of a pin b^5 , which

projects from the part B². The part B² is shown cylindrical at its inner end b^6 , which fits within the flange b^3 and is secured thereto 55 by means of said pin b^5 . The outer end b^7 of this part of the casing is preferably in the shape of a truncated cone with the small end outermost and open. On its inner side it is preferably provided with a series of two or 60 more inwardly-projecting radial vanes b^8 , adapted to cause water which has passed the wheel, hereinafter described, to change its course from a spiral to a rectilinear one. A bearing b^9 , containing a central opening b^{10} , 65 is secured within the mouth b^{11} of the casing by means of bars b^{12} .

C represents a water-wheel having inwardly-projecting buckets c , against which said nozzles a^3 direct jets of water. Its inner 70 end is attached by means of spokes c' to a ring c^2 , encircling said tubular inlet A just inside of the shoulder or flange a^4 , which forms a bearing for it. Its outer end is attached to a brush-holder D by means of spokes c^3 . 75

The brush-holder D has a cylindrical body portion d , which passes through the opening b^{10} in the bearing b^9 , an annular flange or shoulder d' , which rests upon said bearing, a central opening d^2 in its inner end into which 80 the outer end of said rod a^5 projects and assists in keeping the inner end of the wheel C in position, and a socket d^3 in its outer end for the reception of the inner end of a brush-handle. Its side is shown pierced by a screw-hole d^4 for a set-screw d^5 , adapted to keep said brush-handle from escaping from said socket. 85

The brush E shown is of ordinary form and is provided with a handle e , having an end e' , adapted to enter the socket d^3 in said brush-holder. 90

In the form shown said device operates as follows: By turning the cock a^7 water is admitted to the interior of the casing B, and being discharged through the nozzles a^3 against the buckets c of the water-wheel C causes said wheel to revolve rapidly in the direction indicated in Fig. 5 by an arrow. The brush E being rigidly attached to the wheel revolves with it, and the water discharged through the nozzles a^3 after passing through said wheel is caused by the shape of the casing and the radial stationary vanes b^8 to flow out upon the brush, which is thus supplied with the water 95 100

necessary for use in scrubbing, and all that a person using the device has to do is to hold the brush against the surface to be scrubbed.

We have described the preferred form of our device, but we do not desire our claims to be limited to that form, as the forms of the various parts may be widely departed from without departing from the essence of our improvement. There are, for instance, many different forms of water-wheels which are well known and any one of which might be substituted for the wheel shown by any person skilled in the art after reading this specification, without the exercise of anything more than ordinary mechanical skill, and we therefore do not desire to be understood as confining ourselves to the form of wheel shown or to a device in which the water is discharged against the buckets of the wheel in the manner above described, except where such a device is specified in our claims.

We claim—

1. The combination of the casing B composed of the part B', having the slot b⁴, and the part B², having the pin b⁵ for securing said

parts together; a water-wheel within the casing; a tubular water-inlet leading into the casing through its inner end, and having a shoulder a⁴; a bearing b⁹, having a circular opening b¹⁰; means for attaching said bearing to the casing; a holder D rotating within said opening b¹⁰; means for attaching said holder to the water-wheel; a ring encircling said water-inlet, and resting against said shoulder a⁴; and means for attaching said ring to said wheel substantially as described. 30

2. The combination of a casing, a water-wheel C having inwardly-projecting buckets c; a water-inlet; a ring encircling said inlet, spokes connecting the wheel C to said ring; 40 a brush-holder D; spokes c³ connecting the wheel C to said holder; the bearing b⁹ for said holder, having the opening b¹⁰; and a brush having one end in said holder substantially as described.

CHARLES ABRELL.
EDWARD BURJES.
